UNITED STATES PATENT OFFICE.

DAVID ISENBERG, OF MIAMI, FLORIDA.

PAINT.

No Drawing.

Application filed January 30, 1926. Serial No. 85,024.

My invention relates to the manufacture of a paint which can be used with equal efficiency for coating stucco, and as a water color.

5 In order to manufacture my improved paint the following ingredients are to be mixed in substantially the proportions given viz: Water solution of ammonia fifty pounds, potash twenty five pounds, and soap grease twenty five pounds.

10 In using this product, a suitable color liquid is mixed to which my product is added, the proportion having been found

most desirable is one gallon of my product to ten gallons of the color solution. My 15 product adds strength to the color solution makes it waterproof and prevents the color from fading.

What I claim is:

The herein described paint consisting of 20 water solution of ammonia, fifty pounds; potash, twenty-five pounds; soap grease, twenty-five pounds and a water vehicle.

In testimony whereof I affix my signature.

DAVID ISENBERG.
